UNITED STATES PATENT OFFICE.

MARTIN E. SELLE AND DANIEL A. DRISCOLL, OF CHICAGO, ILLINOIS, ASSIGNEES OF ONE-THIRD TO WILLIAM J. DRISCOLL, OF CHICAGO, ILLINOIS.

TABLET-SEPARATOR.

1,320,802.

Specification of Letters Patent.

Patented Nov. 4, 1919.

Application filed July 16, 1919. Serial No. 311,239.

To all whom it may concern:

Be it known that we, MARTIN E. SELLE and DANIEL A. DRISCOLL, citizens of the United States, residing at Chicago, in the county of Cook and State of Illinois, have invented new and useful Improvements in Tablet-Separators, of which the following is a specification.

The apparatus which is the subject matter of the present application for patent has been designed to effect the separation of medicinal and other tablets having a coating which is apt to cause the tablets to stick together when the coating dries. To separate the adhering tablets by hand is a slow process, and the invention therefore has its object to provide a novel and improved apparatus by which the separation is effected automatically and expeditiously.

20 The invention also has for its object to provide a separator which is adjustable to take tablets of various thicknesses.

With the objects stated in view, the invention consists in a combination and arrangement of parts to be hereinafter described and claimed, and in order that the same may be better understood, reference is had to the accompanying drawing forming a part of this specification.

30 In the drawing,

Figure 1 is a perspective view of the apparatus and a supporting means therefor;

Fig. 2 is a cross-section on the line 2—2 of Fig. 3;

35 Fig. 3 is a side elevation of the apparatus, partly in section, and

Fig. 4 is a plan view.

Referring specifically to the drawing, 5 denotes the side walls and 6 the end walls of 40 a frame or receptacle which is open at the top and bottom. Inside this frame, along each side wall, are located two superposed longitudinal bars 7 and 8, respectively. The bottom bars 7 are made fast to the side walls 45 5, and the top bars 8 are slidably supported on said bottom bars so that they may be reciprocated in the direction of their length.

Passing through the bottom bars 7 near one end thereof and extending therebetween, 50 is a rock shaft 9 which also passes through one of the side walls 5 and projects therefrom, and on said projecting end of the rock shaft is fastened an operating lever 10 movable at its free end along a guide segment 55 11 fastened to one of the side walls 5 on the

outside thereof. A set screw 12 fastens the lever 10 at any point on the segment 11.

Inside the frame hereinbefore described, the shaft 9 carries two crank arms 13 having their outer ends forked, as shown at 14, to 60 straddle a rod 14^a extending between and carried by the top bars 8. It will therefore be seen that the two bars 8 may be slid together in the direction of their length when the lever 10 is swung to rock the shaft 9.

65 The bars 7 carry a series of cross rods 15 and the bars 8 carry a series of cross rods 16, these rods being secured to the bars in any suitable manner and extending therebetween. The two sets of rods are arranged 70 in pairs the members of each pair being arranged one above the other, and slightly offset laterally with respect to each other.

Above each top rod 16 are located cross rods 17 which extend between the bars 8 but are 75 not fixed thereto. Each group of cross rods 15, 16 and 17 serve to support one of a series

of co-acting separating elements, composed of a piece of sheet metal which is bent around the rod 17 and has its two ends extending downwardly from opposite sides thereof. One end 18 extends down to the rod 15 and is attached thereto by being rolled around the same, and the other end 19 extends down to, and is secured in a similar 85 manner to the rod 16. These separating elements extend throughout the entire distance between the bars 7 and 8, and as they are spaced apart and parallel, they define downwardly tapered spaces through which the 90 tablets to be separated are forced. The width of these spaces can be readily reduced by sliding the bars 8 in a direction to spread the rods 15 and 16, by which action the parts 18 and 19 are spread. This brings the part 95 18 closer to the part 19 of the adjacent element as shown dotted in Fig. 3, and consequently reduces the space therebetween. The parts 18 and 19 are flexibly or pivotally connected by the rods 17 so that they may be 100 readily spread or drawn closer together according to the spacing desired.

It will be seen that a tablet dropped between two adjacent separating elements must not be greater in thickness than the width of the 105 space between the parts 18 and 19 of said adjacent elements in order to drop through, and hence if two or more tablets are stuck together they will not pass until they are separated. The apparatus is designed to be 110

agitated for the purpose of causing the adhering tablets to separate.

At one end of the apparatus is a sheet metal deflector 20 to protect the shaft 9.

5 To the side walls 5 of the frame are soldered or otherwise secured strips 21 having outstanding flanges 22 which overlap the slide bars 8 and form guides therefor, and also keep dust from falling between the 10 same and the side walls, which would interfere with the free movement of said bars.

The apparatus is set over a large pan 23 into which the separated tablets drop. The apparatus is mounted in a supporting carriage 24 and is agitated by sliding the latter back and forth. The carriage has grooved 15 rollers 25 which ride on the opposite side edges of the pan 23.

The apparatus is moved back and forth in 20 the direction of the length of the separating elements 18 and 19, which facilitates the separation of adhering tablets.

We claim:

1. A tablet separator comprising spaced 25 and parallel cross members each of which has opposite sides which are flexibly connected for spreading or contracting said sides to vary the spacing between adjacent cross members, and an open bottomed receptacle 30 in which the cross members are positioned.

2. A tablet separator comprising spaced and parallel cross members each of which has opposite sides which are flexibly con-

nected, supports for the respective sides of said members, means for moving the supports of one of the sides relative to the supports of the other sides for spreading or contracting said sides to vary the spacing between adjacent cross members, and an open-bottomed receptacle in which the cross 40 members are mounted.

3. A tablet separator comprising spaced and parallel cross members each of which has opposite sides which are flexibly connected, supports for the respective sides of 45 said members, a slideable member carrying the supports of one of the sides, means for shifting said member for moving the last mentioned supports relative to the supports of the other sides for spreading or contracting said sides to vary the spacing between adjacent cross members, and an open-bottomed receptacle in which the cross members are mounted.

4. A tablet separator comprising a series 55 of spaced and parallel cross members each of which has opposite sides which are flexibly connected for spreading or contracting said sides to vary the spacing between adjacent cross members, and a slideably supported 60 open-bottomed receptacle in which the cross members are positioned.

In testimony whereof we affix our signatures.

MARTIN E. SELLE.
DANIEL A. DRISCOLL.
